MAGNETRON

William Ernest Willshaw, Kenton, England, assignor to M-O Valve Company, Ltd., London, England, a limited company of Great Britain

Application November 7, 1946, Serial No. 708,279
In Great Britain April 9, 1942

Section 1, Public Law 690, August 8, 1946
Patent expires April 9, 1962

32 Claims. (Cl. 315—40)

1

This invention relates to electron discharge devices and more particularly to vacuum tubes of the type known as magnetrons.

Magnetrons in various forms are particularly useful for generating high frequency energy at extremely short wave length. A particular form of magnetron over which this invention is an improvement comprises a solid substantially cylindrical block acting as an anode and having plane ends perpendicular to its axis. An axial cylindrical aperture traverses the anode block for housing the axially disposed cathode. A plurality of slots parallel to the axis of the block are radially disposed and open at one end into the cathode aperture and closed at the other end. This construction is commonly known as a multi-segment multi-cavity magnetron.

An object of this invention is to improve the construction of magnetrons of the type referred to and thereby increase their overall efficiency.

Another object of the invention is to provide improved means for coupling the energy from the magnetron to an external circuit.

A particular advantage resulting from the modifications herein proposed is the adaptability of the magnetron to be coupled to various types of load circuits.

Another advantage resulting from the novel construction is a greater uniformity of resonance of the individual cavities of the magnetron.

Other objects and advantages will be apparent from the following description of the invention, pointed out in particularity in the appended claims and taken in connection with the accompanying drawings in which:

Fig. 1 is a sectional view of a magnetron representing one embodiment of the invention;

Fig. 2 is a cross-sectional view of Fig. 1 taken on lines 2—2';

Fig. 3 is a partial view in cross-section of a modification of the structure shown in Fig. 2 for coupling to a wave-guide;

Fig. 4 is a sectional view illustrating a modified structure in accordance with the invention;

Fig. 5 is a cross-sectional view of Fig. 4 taken along lines 5—5';

Fig. 6 is a cross-sectional view of another embodiment showing the coupling to a wave-guide; and

Fig. 7 is a top view in partial cross-section of a modified structure of coupling and cavities.

In known magnetrons of the type described the function of the slots is to act as resonators for the oscillations generated. They may be regarded as transmission lines, having one open

2

end (namely that opening into the central aperture) and a closed end. If r designates the length of a slot (i. e. its dimension parallel to a radius of the cylinder), the slot will be resonant to oscillations whose wave-length is roughly $4r$; the resonant frequency will not vary much with the depth of the slot (i. e. its dimension parallel to the axis).

It is important in such magnetrons that all the slots should be resonant to the same frequency. It is not always easy to achieve this result; partly because the resonant frequency depends on the length of the slot which is not easily controlled to high accuracy; partly because the sides of the slots (i. e. their terminations in planes perpendicular to the axis of the block) are open and may be differently related to conductors such as the discs which usually terminate the cathode at either end, or the leads to the heater by which the cathode is heated.

According to the invention in a magnetron of the type specified the sides of the slots are closed by conducting plates or discs, not integrated with the block, but connected to (preferably abutting against) the block and substantially perpendicular to its axis. When the sides are thus closed by discs, the radial slots thus formed are regarded better as wave-guides than as transmission lines, for the conducting discs prevent them from acting as transmission lines.

Their resonant frequencies depend primarily on the axial depth which is about half the wavelength of the oscillations; it depends less on the radial length, so long as this is not very different from the depth. It is easier to adjust the depth than the length to a given accuracy, because all that is needed is to turn down the ends of the block, whereas the length has to be adjusted by milling, a far less accurate operation. Moreover, when the ends are turned down, all the depths naturally assume the same value, while each length has to be adjusted separately. Also the discs completely shield the interior of the wave-guide (and therefore its natural frequency) from any influence of bodies outside the sides or axial ends of the slot.

However, the problem of coupling the resonators to the load circuit now arises. It cannot be effected, as in the known construction, by loops introduced into the slots from their axial ends, for these are closed. In one method of coupling according to the invention, the slots, instead of being closed at their outer radial ends, open into an annular channel in the block surrounding its axis, and a path is provided where-

50

by energy may pass from the oscillations in the channel to an output circuit outside the block. This path may be provided, for example, by a loop projecting into the channel or by a wave-guide opening into it.

This embodiment of the invention, will now be described, with reference to Figs. 1, 2 and 3 of the drawing.

The anode block is made up of the outer cylindrical copper shell 5, closed at its ends by copper plates 6, and the inner copper block 7 fitting closely within it. The block 7 was originally solid and cylindrical, but the recesses 8, the annular groove 9, and the central hole 10 have been turned or drilled out of it; further twelve longitudinal slots 12 of uniform width, opening into the hole 10 and, for most of their depth, into the groove 9, have been milled in it from end to end. The sides of the slots 12 are then covered by the copper rings or apertured discs 13, leaving the ends of the central hole 10 open. A tubular cathode 14, furnished with end discs 15, is supported centrally in the hole 10 on the leads 17 which enter through seals 18 in the shell 5.

The annular groove 9, closed on its outer side by the shell 5, constitutes an annular channel. In Fig. 2 the loop 19 extending into the channel from a coaxial line 20 in the shell 5 provides the coupling between the annular channel and the external circuit. In the alternative shown in Fig. 3, there is a tapered aperture or coupling chamber aperture or slot 22 in the outer shell 5 through which the annular channel communicates with a circular output wave-guide 23 closed at the far end by the glass diaphragm 24.

In a practical embodiment the following dimensions were chosen:

Depth of slot=18.5 mm.
Length of slot=8.0 mm.
Width of slot=1.0 mm.
Diameter of central hole=12.0 mm.
Depth of annular channel=16.4 mm.
Radial width of annular channel=11.0 mm.
Diameter of cathode=6.0 mm.
The diameter of the block=50 mm.

In this embodiment, the slots and the annular channel now form a single oscillating system, and its dimensions, namely, the depth, length, and width of the slots and the depth and radial width of the channel, must be designed in dependence on each other. But to a first approximation the channel may be regarded as a wave-guide fed by the slots. Then one condition that must be fulfilled is that there is an integral number of complete periods of the electric intensity round the annular channel; another is that the resonant frequencies of the slots, regarded as independent resonators, is above the limit of frequency below which the wave-guide ceases to transmit oscillations. However, it is not in general desirable that the slots should be resonant at the frequency at which the magnetron is designed to operate; better frequency stability may be obtained if they are resonant at a slightly different frequency; the best relation between the resonant frequency of the slots and the operating frequency will depend somewhat on the load that the magnetron feeds. The analogy of a parallel tuned oscillator fed by taps on the inductor is here useful as a guide to design. With these principles in view, the system can usually be designed so that final adjustment of one dimension only is necessary to obtain substantially optimum efficiency; this dimension may conveniently be the

depth of the slots. When the slots 12 are resonant at the operating frequency of the magnetron a high impedance plane will exist at the junction of each slot with the annular channel, in which case the load impedance energized from the annular channel will be reflected with maximum effectiveness into the slots 12.

Referring to Figs. 4 and 5, in this modification a connection between the slots 12 and the annular channel 9 is established by radiator-loop combinations projecting from the latter into the former. For this purpose the slots are expanded at one part, for example, by drilling holes axially enlarging each slot as shown at 26; 27 are the radiators in the annular channel, 27' the loops in the expanded parts. Other parts numbered in Figs. 4 and 5 correspond to those similarly numbered in the aforesaid Figs. 1, 2 and 3.

In a practical embodiment the expanded parts 26 are cylinders 5 mm. in diameter, extending along the whole depth of the slot; the holes 28 through which the loops enter are 4 mm. in diameter. The unexpanded parts are 3 mm. wide on the outer end and 1 mm. wide on the inner end. The whole radial length of the slot is therefore now (5+3+1=9 mm. in place of 8 mm. But the annular channel 9 is now only 10 mm. in radial width. The radiators 27 as well as the loop 19 each project 5 mm. into the channel 9.

In another method of coupling, illustrated in Fig. 6 one of the slots 12 is extended and opens into an output wave-guide 23 of circular cross-section mounted on the shell 5; a transitional tapered aperture or channel 22 connects the slot proper into the wave-guide. The outer ends of the other slots 12 are closed. Each slot may be considered a cavity resonator. Communication with the atmosphere is prevented by closing the outer end of the wave-guide 23 by a glass disc 24. Energy may then be led away by sliding another circular wave-guide over the aforesaid wave-guide 23.

A modification which has some resemblance to that shown in Fig. 4 is shown in Fig. 7. Here a single loop 28 introduced through a seal 29 on the outside of the block enters into a single slot which has an enlarged closed outer end 30. The other slots 12 have similar outer ends, in order that they may also be resonant at the same frequency. As in Fig. 6 the slots form cavity resonators. It will be observed that this method differs from the method used in the known devices which do not have side plates according to my invention mainly in the introduction of the loop into the outer end of a slot instead of into its side. In Fig. 7 the total lengths of the slots may be 16 mm., the diameter of the enlarged end 5 mm.

I claim:

1. In an electron discharge device, a cylindrical anode block having a central chamber extending along the longitudinal axis thereof and an annular chamber adjacent the outer surface thereof, said block having slots of uniform width extending between said chambers for communication therebetween and means coupled with said annular chamber for transferring energy from said device.
2. In an electron discharge device, a cylindrical anode block having a central chamber extending along the longitudinal axis thereof and an annular chamber adjacent the outer surface thereof, said block having slots of uniform width extending between said chambers for communication therebetween and means including a loop in said

annular chamber and extending from said device for transferring energy therefrom.

3. In an electron discharge device, a cylindrical anode block having a central chamber extending along the longitudinal axis thereof and an annular chamber adjacent the outer surface thereof, said block having slots extending between said chambers for communication therebetween and means including a wave-guide opening into said annular chamber for transferring energy from said device.

4. In an electron discharge device of the magnetron type, a cylindrical anode block having a plurality of radially extending slots of uniform width therein terminating at one end near the center of said block and opening into a central chamber, said block having an annular channel surrounding and opening into the other ends of said slots, conducting plates covering the sides of said slots whereby said slots form cavities which are closed except at said ends, and means for transferring energy from said magnetron comprising a portion of said block having an opening extending into said channel and a loop in said channel extending through said opening to the exterior of said block.

5. In an electron discharge device of the magnetron type, a cylindrical anode block having a plurality of radially extending slots therein terminating at one end near the center of said block and opening into a central chamber, said block having an annular channel surrounding and opening into the other ends of said slots, conducting plates covering the sides of said slots whereby said slots form cavities which are closed except at said ends, and means for transferring energy from said magnetron comprising a portion of said block having a tapered aperture opening at its narrow end into said channel and at its wider end into a wave-guide mounted on the outer surface of the block at one end and hermetically sealed at its outer end.

6. In an electron discharge device of the magnetron type, a cylindrical anode block having a plurality of radially extending slots therein, each of said slots having an inner open end near the center of said block and an outer open end toward the outside thereof, said block having an annular channel surrounding said slots and opening into said outer open ends, said slots having expanded portions, a coupling loop in each said portion extending into said channel, conducting plates covering the sides of said slots whereby said slots form cavities closed except at said open ends, and means for transferring energy from said magnetron comprising a portion of said block having an aperture opening into said channel and a loop in said channel extending through said aperture to the exterior of said block.

7. In an electron discharge device of the magnetron type, a cylindrical anode block having a plurality of radially extending slots therein, each of said slots being closed on all sides and having an inner open end near the center of said block and an expanded portion toward the outside of said block, means for transferring energy from said magnetron comprising a portion of said block having an aperture opening into said expanded portion of one of said slots and a loop in said portion extending through said aperture to the exterior of said block.

8. In an electron discharge device of the magnetron type, a cylindrical anode block having a plurality of radially extending slots of uniform width therein, each of said slots having an inner

open end near the center of said block and all but one of said slots having an outer closed end, conducting plates covering the sides of said slots whereby said slots form closed cavities, means for transferring energy from said magnetron comprising a portion of said block having a tapered aperture opening at its narrow end into said one of said slots and at its wider end into a wave-guide mounted on the outer surface of the block at one end and hermetically sealed at its outer end.

9. In an electron discharge device of the magnetron type, a cylindrical anode block having a plurality of radially extending slots of uniform width therein terminating at one end near the center of said block and opening into a central chamber, said block having an annular channel surrounding and opening into the other ends of said slots, conducting plates covering the sides of said slots whereby said slots form cavities which are closed except at said ends, and means for transferring energy from said magnetron.

10. In an electron discharge device, a cylindrical anode block having a central chamber extending along the longitudinal axis thereof and having radially extending slots opening at their inner ends into said channel chamber, said slots having uniform width for at least a part of their radial length, conducting plates contacting the ends of said anode block at the sides of said slots whereby said slots are closed on all sides, and means coupled to at least one of said slots for transferring energy from said discharge device.

11. An electron discharge device in accordance with claim 10, wherein said energy transferring means comprises an aperture in the wall of said anode block coupled to at least one of said slots and opening into a hollow wave guide hermetically sealed to said block at one end and hermetically sealed at its outer end.

12. An electron discharge device in accordance with claim 11, wherein said aperture is tapered with at least two side walls thereof diverging from said resonator toward said wave guide.

13. An electron discharge device comprising a cavity resonator, means for establishing a high frequency electric field within said resonator, said resonator having an aperture extending through a wall thereof, a hollow wave guide hermetically sealed at one end to said resonator in registration with said aperture, and means permeable to electromagnetic waves hermetically sealing the other end of said wave guide, said aperture being tapered with at least two side walls thereof diverging from said resonator toward said wave guide.

14. An apparatus for use at high frequencies comprising a cavity resonator and means for transferring electromagnetic energy from said resonator comprising an aperture in a wall of said resonator, a hollow wave guide hermetically sealed at one end to said resonator in registration with said aperture, and means permeable to electromagnetic waves hermetically sealing the other end of said wave guide, said aperture being tapered, with at least two side walls thereof diverging from said resonator toward said wave guide.

15. An electron discharge device of the magnetron type comprising a cathode surrounded by an anode assembly, said anode assembly including a plurality of cavity resonators, a metallic envelope enclosing said anode assembly and cathode, the wall of said envelope having an aperture therethrough registering with one of said

cavity resonators, means coupling said one cavity resonator with said aperture, a hollow wave guide hermetically sealed at one end to said envelope in registration with said aperture, and means permeable to electromagnetic waves hermetically sealing the other end of said wave guide.

16. An electron discharge device in accordance with claim 15, wherein said aperture is tapered, with at least two side walls diverging from said one resonator toward said wave guide.

17. An electron discharge device of the magnetron type comprising an envelope of conducting material containing a cylindrical anode block having a central chamber extending along the longitudinal axis thereof and a plurality of radially extending slots of uniform width opening at their inner ends into said central chamber, said envelope having an aperture therethrough registering with the outer end of one of said slots, means for coupling said one slot electromagnetically with said aperture, and an output wave guide sealed at one end to said envelope in registration with said aperture and having means permeable to electromagnetic waves sealing the other end thereof.

18. An electron discharge device according to claim 17, wherein said aperture is bounded by side walls which diverge toward the outside of said envelope.

19. An electron discharge device including a cathode and an anode block having a central chamber, said cathode being within said chamber, said anode block having a plurality of radially extending slots of uniform width communicating with the chamber between the cathode and the anode block and forming resonators, the end of one of said slots remote from said cathode opening into a coupling chamber having side walls diverging toward the outside of said anode block, and a tubular output lead extending from said block and opening into said coupling chamber.

20. An electron discharge device including an anode block, said anode block being provided with a central chamber and having a plurality of radially extending slots of uniform width communicating with said chamber, a cathode mounted within said chamber, the end of one of said slots remote from said cathode opening into a coupling chamber having side walls diverging toward the outside of said anode block, a tubular output lead extending from said block and having one end opening into said coupling chamber and having its other end sealed by a closure member permeable to electromagnetic waves.

21. An electron discharge device including a cathode and an anode block having a central chamber, said cathode being within said chamber, said anode block having a plurality of radially extending slots of uniform width communicating with the chamber between the cathode and the anode block and forming resonators, the end of one of said slots remote from said cathode being coupled electromagnetically with a coupling chamber having side walls diverging toward the outside of said anode block, and a tubular output lead extending from said block and opening into said coupling chamber.

22. An electron discharge device including an anode block, said anode block being provided with a central chamber and having a plurality of radially extending slots of uniform width communicating with said chamber, a cathode mounted within said chamber, the end of one of said slots remote from said cathode being coupled elec-

tromagnetically with a coupling chamber having side walls diverging toward the outside of said anode block, a tubular output lead extending from said block and having one end opening into said coupling chamber and having its other end sealed by a closure member permeable to electromagnetic waves.

23. A high-frequency oscillator comprising: an electron discharge tube having a plurality of primary cavity resonators therein; and a secondary cavity resonator opening into and adapted to be excited from said primary cavity resonators; said primary cavity resonators being spaced with respect to each other whereby in-phase oscillatory energy therefrom enters into said secondary cavity resonator at a plurality of points spaced along the same.

24. An electron discharge device comprising: a cathode; an anode; said anode having a plurality of grooves therein and an electron-receiving portion intermediate each pair of adjacent grooves; said grooves constituting primary cavity resonators; and a secondary cavity resonator opening into and adapted to be excited from said primary cavity resonators.

25. An electron discharge device comprising: a cathode; an anode; said anode having a plurality of grooves therein and an electron-receiving portion intermediate each pair of adjacent grooves; said grooves constituting primary cavity resonators; and a secondary cavity resonator opening into and adapted to be excited from said primary cavity resonators; said primary cavity resonators being spaced with respect to each other, whereby in-phase oscillatory energy therefrom enters into said secondary cavity resonator at a plurality of points spaced along the same.

26. A high-frequency oscillator comprising: an electron discharge tube having a plurality of primary cavity resonators therein; and a secondary cavity resonator directly coupled to and adapted to be excited from said primary cavity resonators.

27. A high-frequency oscillator comprising: an electron discharge tube having a plurality of primary cavity resonators therein, and a secondary cavity resonator directly coupled to and adapted to be excited from said primary cavity resonators; and means coupled to said secondary cavity resonator for leading oscillator energy out of the same.

28. An electron discharge device comprising: a cathode; an anode; said anode including a block of conducting material provided with a central bore receptive of said cathode; said block including a plurality of slots extending from said central bore to the exterior wall thereof to form a plurality of electron-receiving portions separated by a plurality of primary cavity resonators; and annular channel means connected to said block and cooperating with said exterior wall to form a secondary cavity resonator; said primary cavity resonators opening into said secondary cavity resonator.

29. An electron discharge device comprising: a cathode; an anode; said anode including a block of conducting material provided with a central bore receptive of said cathode; said block including a plurality of slots extending from said central bore to the exterior wall thereof to form a plurality of electron-receiving portions separated by a plurality of primary cavity resonators; and annular channel means connected to said block and cooperating with said exterior wall to form a secondary cavity resonator; said primary cavity resonators opening into said sec-

ondary cavity resonator at high impedance planes.

30. An electron discharge device comprising: a cathode; an anode; said anode including a block of conducting material provided with a central bore receptive of said cathode; said block including a plurality of slots extending from said central bore to the exterior wall thereof to form a plurality of electron-receiving portions separated by a plurality of primary cavity resonators; annular channel means connected to said block and cooperating with said exterior wall to form a secondary cavity resonator; and conducting rings at least partially closing opposite sides of said block; said primary cavity resonators opening into said secondary cavity resonator.

31. A electron discharge device comprising: an envelope enclosing a cathode and an anode structure; said anode structure including a plurality of anode elements forming a plurality of cavity resonators each of which is adapted to resonate at a predetermined output frequency; a common cavity resonator adapted to resonate at said predetermined output frequency; and a plurality of coupling devices coupled to said common cavity resonator; said coupling devices also being coupled, respectively, to some of said first-named cavity resonators which are spaced from each other by a distance equal to an integral number of wave length corresponding to said predetermined output frequency.

32. An electron discharge device having a hollow drum-shaped conducting member, a plurality of anode elements of sector-shaped transverse section mounted within said member in spaced relation thereto, whereby the inner wall of said drum-shaped member and the outer surface of said sector-shaped anode elements provide a cavity resonator, said anode element being spaced from each other along radial planes to provide radially-directed slots, the inner ends of said anode elements providing anode segments defining a cathode chamber, a cathode mounted in said chamber, said slots being resonant at the operating frequency of said device.
